INVENTOR.

Thomas Lund

UNITED STATES PATENT OFFICE.

THOMAS LUND, OF BEVERLY, MASSACHUSETTS, ASSIGNOR TO UNITED SHOE MACHINERY CORPORATION, OF PATERSON, NEW JERSEY, A CORPORATION OF NEW JERSEY.

APPARATUS FOR AND METHOD OF TREATING HEELS.

1,384,139.

Specification of Letters Patent. Patented July 12, 1921.

Application filed July 19, 1918. Serial No. 245,705.

To all whom it may concern:

Be it known that I, THOMAS LUND, a citizen of the United States, residing at Beverly, in the county of Essex and State of Massachusetts, have invented certain Improvements in Apparatus for and Methods of Treating Heels, of which the following description, in connection with the accompanying drawings, is a specification, like reference characters on the drawings indicating like parts in the several figures.

This invention relates to apparatus for and method of preparing heels for compression.

It has been found in practice that one effective way to produce heels is to build them with paste as a connector between the lifts, with or without nailing them, then to hold them under pressure until the right "condition" of the heel has been attained by the partial "setting" of the paste and the absorption of a portion of the moisture of the paste by the lift materials, and then to subject them to heavy compression while they are in the proper condition. The time required for thus "conditioning" heels preparatory to compression varies with the heel stock, the kind of paste used, and the humidity and temperature of the atmosphere. Satisfactory results are, however, dependent to a large degree upon the pressure with which the heel is held. Experiments have shown that variations in pressure within practical limits multiply manifold the rapidity with which the "conditioning" of the heels takes place. It follows that, when a heel system has been organized to subject the heels to the right degree and duration of pressure to condition them properly for compression, any heels which get substantially less than the intended pressure are non-uniform with the properly pressed heels. Great difficulty is experienced in practice in obtaining uniform pressure, largely because of the fact that the heel stock, or "lifting," varies in thickness, as well as in density. As the heels come from the builder to the press they differ substantially from one another in height despite all the care it is practical to exercise. To deal with this situation apparatus has been devised to subject heels to pressure individually as for example, of the Ferris wheel type illustrated in Hudson Patent No. 1,156,842. This is obviously an ex-

pensive and space-consuming apparatus when provided to hold the heels under pressure for any considerable length of time. The popular system of heel pressing, therefore, is that which has been in use for many years in which the girl who builds pasted heels transfers each heel, wet with paste, from the building device to a board conveniently located at her side. The board is usually large enough to hold four rows of five men's heels. After the board has been filled, it is transferred to a press in which it is stacked with other filled boards to the height or capacity of the press, which may vary from 20 to 60 boards, according to the height of the heels being made. The press may be of any known or suitable type, such for example as a screw press having a stationary foot plate and a platen forced downwardly upon the stack of loaded heel boards by a hand-wheel operated screw.

In a board press system the heels on each board are subjected in parallel to pressure between the top face of that board and the lower face of the superposed board. It is obvious that in such an arrangement the highest three or four heels on a board get the maximum pressure and if any heels on the board are substantially lower than those highest ones, the high heels prevent the boards from subjecting such low heels to pressure. The result is that one can usually reach into a press while the pressure is on and find some heels that are under no pressure, as evidenced by the fact that they can be moved sidewise between the boards by the finger. These heels obviously will dry with the lifts in loose relation to one another and not be properly conditioned for compressing and the product will be relatively inferior heels.

It is the object of this invention to effect such improvement in apparatus for and methods of treating heels as to render this popular system of making heels free or relatively free from the defects or objections, an illustrative example of which has been above pointed out.

With this object in view one feature of this invention consists in a heel board of dimensions to hold a plurality of heels in an apparatus for pressing heels and having a cushion heel-engaging face. Another feature of the invention consists in an appa-

ratus for treating heels comprising a press and a plurality of superposed heel boards in which each upper board covers the heels on a lower board and in which boards have 5 pressure faces constructed and arranged to distribute the pressure of the press upon the high and also upon the low heels. The pressure surfaces may be cushions, springs, or a facing of compressible material into which 10 the high heels can sink far enough to permit pressure transmitting engagement with the heels that are slightly lower, as for example by reason of non-uniformity in the thickness of different pieces of heel lifting. The pressure 15 distributing surface may be on the heel supporting side of the board or on the heel covering side. In another of its aspects this invention comprises that improvement in methods of treating heels which consists in 20 arranging upon a board a plurality of heels of approximately the same height, covering the heels and applying pressure and transmitting the pressure to individual heels on the board through individually yielding 25 transmitters capable of taking up any variation that occurs in the height of the heels on the board.

The invention in its various aspects and features will be more definitely pointed out 30 in the claims found at the end of the following description of an illustrative embodiment of the mechanical features of the invention and of a manner of using the improvements.

Figure 1 of the drawings is a perspective view of one familiar type of press for treating heels and shows one form of heel boards embodying this invention.

Fig. 2 shows on a larger scale the form of 40 heel boards shown in Fig. 1, together with wedge lift heels held under uniform pressure at their higher and lower edges between such boards.

Fig. 3 shows different forms of heel boards 45 embodying this invention.

Fig. 4 shows a further modification.

The press shown in Fig. 1 comprises a base 2 from which extend vertical risers 4 on which slide the sleeves at the end of a 50 pressure head 5. The pressure head is operated by a screw 6 having a hand wheel 8 and threaded in a screw carrier 10 that is adapted to be fixed at different elevations on risers 4 by means of locking devices 12 co- 55 operating with sleeves 14 and the rods 15. The construction of these parts of the press forms no part of the present invention and it should be understood that any known or suitable form of press may be employed in 60 connection with the present invention.

The board may be of the usual heel board size and should permit at least four heels to be arranged on it, the same being shown as carrying four rows of five each of men's 65 heels. The base 20 of the board may be

made of suitable timber such as pine and is preferably thick enough (about three-quarters of an inch) to be comparatively rigid, although the base may be so constructed as to be flexible and in the forms shown in Figs. 7 1, 2 and 4 the base 20 may be of thin sheet metal.

The board is provided on one or both of its sides, and it may be either the heel supporting side or the heel covering side, with a cushion heel-engaging face. In Fig. 1 this cushion face is shown as comprising yielding studs 25 upheld by springs 26 confined within sleeves 28 set in bores in an intermediate piece 30. The studs project through a confining plate 32 and have shoulders 33 to prevent the springs from raising them out of the plate. The studs 25 constituting the cushion face of the boards in Figs. 1 and 2 are preferably close enough together to present several studs as the support for each heel, thus enabling the studs to adjust themselves relatively and apply pressure to both the low and the high parts of a heel containing a wedge lift such as indicated at w.

In Fig. 3 the base 20 of the board is provided with a cushion face 35 of suitably soft rubber or similar material. Paste deteriorates rubber and therefore this cushion face 35 is preferably used on the bottom or heel covering face of the board where it engages the uppermost lift of the heel the top face of which is frequently free from paste. The face 35 may be ribbed or knobbed to present alternate raised and relatively depressed surfaces corresponding to the surfaces presented at 25, 32 in Fig. 2. The high heels, or the high portions of a wedge-lift heel, embed themselves in the cushion surface 35 far enough to bring the lower heels or portions of heels into contact with other portions of the cushion. This insures the transmission of pressure through the board and cushion to all heels of approximately the same height and to the low portions of heels having a wedge lift.

In Fig. 4 a third form of yielding surfaced heel board is shown in which metal leaf springs 40, slit at frequent intervals and overlapped to provide a series of spring fingers 42, are attached to the base member 20 of the heel board, and as shown, to the lower side or heel covering side of the board.

In the use of the invention, boards constructed and arranged as shown, or otherwise, to perform the function described, have heels arranged upon them as heels are customarily arranged upon heel boards by the girls who build heels with paste. When a board has been filled it is superposed on other filled boards in a press or another board is superposed on the heels to cover them, and pressure is applied perpendicular to the faces of the boards. The degree of pressure is at least sufficient to sink the

- higher heels into the cushion face of the boards until the low heels also are firmly held under pressure. The pressure thus applied through the cushion faces of the boards will be near enough to uniform for all heels built under reasonable conditions to afford satisfactory results. By this method the different portions of the cushion face yield to different extents and apply individual pressure to individual heels. This result is particularly well assured by the use of such cushion surfaces as the separate studs 25, fingers 42 and the knobby or the ribbed surfaces shown in Fig. 3.
- 15 The heels shrink more or less if they remain in the press for long and the cushion faced boards have the advantage of expanding to take up the space caused by such shrinkage and maintain the pressure substantially uniform while the heels are in the press.
- Having thus described my invention, what I claim as new and desire to secure by Letters Patent of the United States is:—
- 25 1. Apparatus for treating heels comprising, in combination, a press, and a heel-carrying board for insertion therein, said board having a heel engaging face constructed and arranged for equalizing pressure on heels 30 of varying height.
2. Apparatus for treating heels comprising, in combination, a press, and a heel-carrying board for insertion therein, said board having a heel engaging face constructed and arranged to allow high heels to sink into it and to extend down to engage and to apply pressure to a slightly lower heel located adjacent to a high heel.
3. Apparatus for treating heels comprising, in combination, a press, and a heel-carrying board for insertion therein, said board having a heel engaging face constructed and arranged to permit such relative movement in the direction of the pressure between the 45 portions of its face engaging different heels as to tend to equalize the pressure applied to heels one of which is lower than another.
4. Apparatus for treating heels comprising, in combination, a press, and a heel-carrying board for insertion therein, said board having a cushion heel engaging face.
5. Apparatus for treating heels comprising, in combination, a plurality of superimposed heel boards, each of dimensions to receive a plurality of heels, and means for relatively operating the boards to apply pressure to heels therebetween, each of said boards having a cushion lower face adapted to distribute the pressure over adjacent heels 55 carried by the next lower board and differing from one another slightly in height.
6. Apparatus for treating heels comprising, in combination, a plurality of heel boards, each of dimensions to receive a plurality of heels, a board or cover above the uppermost heel board, and means for relatively operating the boards and cover to apply pressure to the heels, each of said heel boards having alternate raised and depressed surfaces, the raised surfaces being 70 yielding, but offering sufficient resistance to yielding to secure the heel lifts together.
7. For an apparatus for pressing heels, a portable heel board of dimensions to hold a plurality of heels and comprising a relatively rigid base with a heel engaging surface adapted to yield to an extent to take up slight variations in the height of heels intended to be of uniform height and another unyielding surface. 80
8. For an apparatus for pressing heels, a heel board of dimensions to hold a plurality of heels, having relatively yielding heel engaging members on one of its surfaces adapted to distribute pressure with approximate uniformity over a charge of heels which differ slightly from one another in height, and having a rigid heel engaging surface on its opposite face. 85
9. For an apparatus for pressing heels, a heel board of dimensions to hold a plurality of heels, one heel engaging face of which is flexible, enabling it to bend up over a high heel and down into pressing engagement with a low heel and another heel-engaging 95 face of which is unyielding.
10. For an apparatus for pressing heels, a heel board of dimensions to hold a plurality of heels and having a cushion heel-engaging face and another heel-engaging 100 face which is rigid.
11. For an apparatus for pressing heels, a heel board of dimensions to hold a plurality of heels and having a cushion face on its lower side through which to apply 105 pressure to heels covered by the board in a stack of boards and heels in a heel press and a rigid heel supporting face on its upper side.
12. That improvement in methods of 110 treating heels which consists in arranging side by side a plurality of heels of approximately the same height, covering the heels, subjecting the heels in parallel to pressure, and distributing the pressure substantially 115 uniformly between the low and the high heels.
13. That improvement in methods of 120 treating heels which consists in arranging side by side a plurality of heels of approximately the same height, and effecting pressure of each of the plurality of heels simultaneously and with substantial uniformity by applying to the heels in parallel pressure which is sufficiently yielding to take up any 125 lack of uniformity in the height of the heels but sufficient in degree to insure that each heel shall be firmly pressed.
14. That improvement in methods of 130 treating heels which consists in arranging

them in a plurality of layers, each layer containing a plurality of heels, applying pressure in a direction normal to the planes of the layers, and distributing the pressure between the individual heels of each layer, regardless of variations in the height of the heels.

15. That improvement in methods of treating heels which consists in arranging them in a plurality of layers, each layer containing a plurality of heels, applying pressure in a direction normal to the planes of the layers, and yieldingly distributing the pressure between the individual heels of each layer.

16. That improvement in methods of

treating heels which consists in arranging in layers a plurality of heels of approximately the same height, applying pressure yieldingly through successive layers of heels and maintaining the pressure upon the heels substantially constant as the heels shrink.

17. That improvement in methods of treating heels which consists in arranging a plurality of heels side by side, applying pressure yieldingly to the heels simultaneously, and maintaining the pressure upon the heels substantially constant as the heels shrink.

In testimony whereof I have signed my name to this specification.

THOMAS LUND.
